HYDRAULIC PRESSURE BOOSTER

Albert S. Kux, Chicago, Ill., assignor to Kux Machine Company, Chicago, Ill., a corporation of Illinois

Application July 22, 1948, Serial No. 40,039

2 Claims. (Cl. 60—54.5)

1

This invention relates to hydraulic pressure multipliers or boosters.

One of the objects of my invention is the provision of a hydraulic device having pistons of different diameters and which acts to produce during a portion of the stroke of a reciprocating mechanism a desired increased force. Such a device as is herein contemplated is particularly useful for operating die casting machines, where in order to obtain castings of uniform density free from voids, it has been found necessary to apply pressure in two successive stages on the injection plunger in injecting the molten metal in a mold, the secondary application of pressure following immediately the first, but being intensified or multiplied during a portion of the final travel of the plunger stroke.

Another object of my invention is the provision of a device of the foregoing character in which the travel of the piston rod is extended or continued after the secondary application of pressure, so that when the device is used in connection with the operation of a die casting machine, as above described, the piston rod will act to eject the slug or sprue of chilled metal from the mold.

A further object of my invention is the provision of a device of the character set forth which is self contained and which is fully automatic in its operation.

Other and further objects of my invention will be apparent from the following description taken in connection with the accompanying drawings in which:

Fig. 1 is a vertical sectional view of a device embodying my invention, in one of its operating positions.

Fig. 2 is a horizontal cross sectional view of the casing along the longitudinal axis of the valve cylinder bore, the section being taken substantially on line 2—2 of Fig. 1.

Fig. 3 is a vertical sectional view taken substantially on line 3—3 of Fig. 2.

Fig. 4 is a similar view taken substantially on line 4—4 of Fig. 2.

Referring to the drawings wherein is shown a preferred embodiment of my invention, the numeral 10 designates generally a casing in which is formed a cylinder having a high pressure bore 11 and an enlarged low pressure bore 12 in axial alignment with a differential piston indicated generally by 13 reciprocating therein. The casing 10 is provided at one end with a member 14 secured thereto in fluid tight relationship. At the other end of the casing and also secured

thereto in similar fluid tight relationship is a cylinder casing indicated generally by 16 and hereinafter to be described in which a piston 17 and piston rod 18 are arranged to reciprocate.

Formed in the casing 10 below the cylinders 11 and 12 is a valve cylinder having bores 19 and 20 in which are received for reciprocating movement a spool valve indicated generally by 21. The valve cylinder bore 19 is provided with inlet port 22 connected to a pressure fluid supply conduit 25, and exhaust port 23 connected to exhaust conduit 30, and communicates with the cylinder bore 11 through passages 24 and 26 and with cylinder bore 12 through passages 27 and 28, the latter being formed in the end member 14. The valve cylinder bores 19 and 20 communicate with cylinder bore 12 through passages 29, 31, and 32, and the bore 12 communicates with exhaust port 23 through passages 33, 31, and 32.

The end member 14 is provided with a bore 36 axially aligned with the cylinder bores 11 and 12. The bore 36 communicates with cylinder bore 11 through passage 37, exterior piping 38, check valve 39 and passage 41. It will be understood that pressure gages may be connected into the piping circuit at points 40a and 40b to register the pressures in cylinder bores 11 and 12 at any particular time of operation.

The differential piston 13 comprises a high pressure piston head 42 and an integral enlarged low pressure piston head 43 reciprocable in cylinder bores 11 and 12 respectively. Integrally formed with the piston head 43 in coaxial alignment is a plug valve 44 reciprocable in the bore 36.

The spool valve 21 is provided with an enlarged head 46 receivable in bore 20, and a body portion 47 receivable in bore 19, the said body portion being provided with annular recesses 48 and 50. The spool valve 21 is bored for a portion of its length to receive a compressing spring 51, the tension of the spring being adjustable by means of a square headed threaded stem 52 in threaded engagement with end member 14 and having a shoulder 53 which engages one end of the said spring. As will be apparent, the spring normally urges the spool valve to the left from the position seen in Fig. 1.

The cylinder casing 16 comprises a tubular portion having a bore 54 in coaxial alignment with bores 11 and 12. The portion of the casing 16 through which the piston rod 18 extends is sealed by packing 56 confined by a packing gland 57. The casing 16 is provided with an inlet port 58 connected to a pressure fluid supply con-

duit 59 which communicates with cylinder bore 54 through passages 61 and 62. A conduit 63 provides communication between passage 61 and cylinder bore 20. The casing 16 is provided with a plugged vent 64 which communicates with cylinder bore 54, the vent serving to exhaust any air that may be trapped in the cylinder bore 54.

The piston 17 and piston rod 18 are suitably secured together in rigid relationship and reciprocate in bore 54. The piston rod 18 may be 10 secured in any suitable manner to any mechanism or device operable by longitudinal motion and is particularly useful for operating the injection plunger of a die casting machine or a like device requiring intensified pressure during a portion of the final travel of the plunger stroke.

The device shown in the drawings is intended to be used preferably with a four-way directional valve not shown connected to conduits 25 and 59 and to a suitable pump, although any other suitable means for controlling the flow of hydraulic fluid may be used.

The operation of the device will now be described:

Fig. 1 of the drawings shows the device about to begin a power stroke to the right. Previously pressure fluid had been admitted into conduit 59, the said fluid passing through passages 61 and 62 into bore 54 to move piston 17 to the right, the said fluid also passing through passage 63 into bore 20 to act on valve head 46 to move the same to the position illustrated in Fig. 1. A four-way valve is actuated to admit hydraulic fluid under pressure through conduit 25 into port 22, the fluid flowing through bore 19 and recess 48 of valve 21, through passages 24 and 26 into cylinder bore 11. When pressure fluid is being admitted into conduit 25 the four way valve acts to restrict the return flow of fluid in conduit 59. Under the conditions mentioned the piston 17 and piston rod 18 proceed to move to the left, the fluid in cylinder bore 54 being caused to pass into passages 62 and 61 and into conduit 59. Also, this fluid will transmit pressure through the fluid in conduit 63 and in the cylinder bore 20 on piston 46 maintaining the valve 21 in the position illustrated in Fig. 1 so that pressure fluid may continue to flow as above described into cylinder bore 11.

When a predetermined resistance to the travel of the piston 17 takes place during the primary application of pressure by the piston 17, when as in the case of a die casting operation the metal is forced into the mold until the surface hardening of the molten metal stops the further advance of the piston, a reduction in back pressure acting on the valve head 46 resulting from the arresting of motion of piston 17 and the continued discharge or draining of fluid through passages 61 and 62 relieves the pressure in conduit 63 and cylinder bore 20 and thereby causes the spring biased valve 21 to move to the left. The flow of pressure fluid into passage 24 is thereby shut off and admitted into passages 27 and 28 and the right end of cylinder bore 12. Under the conditions mentioned, the differential piston 13 proceeds to move to the left and, through the medium of the hydraulic fluid confined in the bore 11 and in the communicating passages such as 26 and 41, transmits the total force acting on the enlarged piston head 43 to the head of piston 17 which has a smaller circular surface area than that of piston head 43, thereby multiplying the unit pressure on the head of piston 17 by the ratio of the circular areas of piston head 43 and piston 70 head 17.

17. Thus, the secondary application of pressure by piston 17 follows immediately the first, but is intensified or multiplied to a desired degree during a portion of the final travel of the stroke of the piston.

It will be seen in the travel of differential piston 13 that so long as plug 44 is disposed within the bore 36, the port to passage 37 is closed and pressure fluid can act only on piston head 43. However, the length of travel of piston 13 in the bore 12 is greater than the length of plug 44. Consequently, during the final travel of piston 13 the plug 44 is withdrawn completely from the bore 36 thereby opening said bore to pressure fluid which enters cylinder 12 and also uncovering the port to passage 37. Pressure fluid then passes through passage 37, piping 38, check valve 39 and into cylinder bore 11 where it acts on piston 17 to cause the same to travel farther to the left. This extended movement of piston 17 coming after the secondary application of pressure is utilized advantageously in ejecting a slug or sprue of chilled metal from a mold when the device is used in connection with the operation of a die casting machine. Any seepage of fluid in the bore 12 in the chamber to the left of piston head 43 is discharged through passages 32, 33, and 34 communicating with the exhaust conduit 30.

In order to effect return movement of the piston rod 18, the flow of fluid is reversed by actuation of a four-way valve and pressure fluid enters into conduit 59 from which it passes through passages 61 and 62 into cylinder bore 54 and through conduit 63 into cylinder bore 20. The fluid acting on the left hand face of piston 17 causes it to travel to the right. Pressure applied to piston 17 is transmitted through the fluid confined in cylinder 11 to piston head 42 to cause piston 13 to move to the right. In the course of such movement fluid in cylinder 12 at the right side of piston 43 is drained through passages 28 and 27, bore 19, passage 35, bore 31, and passage 33 into exhaust conduit 30. Also some of the fluid is forced into passage 37 through piping 38 and check valve 39 into bore 11. Simultaneously with the return movement of piston 17, pressure fluid passing from passage 61 through conduit 63 into bore 20 acts on the valve head 46 and causes the spool valve 21 to move to the right, thereby conditioning the parts so that when the four-way valve is again operated to direct pressure fluid to conduit 25, the fluid will pass through passages 24 and 26 into cylinder bore 11 and drive piston 17 to the left. Thereafter the cycle of operation hereinabove described is repeated.

It will be apparent from the foregoing description that I have provided a self contained device automatically operable to apply pressure in two successive stages, a primary application of a relatively lower pressure during the first portion of travel of the piston rod and a secondary application of a relatively higher pressure during a portion of the final travel thereof, the latter application of pressure being multiplied and of a magnitude several times that of the former. Additionally, the device is automatically operable to provide an extended travel of the piston rod after the secondary application of pressure. It will also be apparent that the transition from the lower pressure to higher pressure cycle is not determined by any particular position of the piston 17 in its travel, but rather is determined by a change of pressure in the pressure fluid which

occurs when the piston rod meets a force resisting its travel.

I claim:

1. A self contained unitary structure of the type described comprising a housing having a relatively large cylinder bore and a communicating relatively small cylinder bore, a unitary differential piston having two diameters and arranged for reciprocation in corresponding cylinders, a second piston disposed in a cylinder communicating with said small cylinder and adapted to be activated by fluid under pressure, said second piston being constantly spaced from said differential piston by a fluid column, said housing having a valve cylinder therein and having ports communicating with ports in said large and small cylinders and with pressure fluid supply means, a spring biased spool valve member longitudinally shiftable in said valve cylinder for controlling the actuation of said differential and said second piston and operable to first direct pressure fluid to act on said second piston for a portion of its travel and then automatically operable, upon said piston encountering a predetermined restraining force, to direct pressure fluid to the large cylinder for actuating the piston therein thereby to transmit through the medium of the fluid confined between said second piston and the small diameter of said differential piston a force of increased intensity during the next portion of travel of said second piston, and valve means including a cylindrical extension on said large diameter piston, said extension adapted to be slidably receivable in an end cylinder communicating with said large cylinder, a conduit connecting said end cylinder with said small cylinder, said extension for a portion of the travel of said differential piston closing communication between said large cylinder and said small cylinder, but at the end of its travel opening affording communication through said conduit whereby pressure fluid is directed therethrough to said small cylinder to act on said second piston for the completion of its stroke.

2. A self contained unitary structure of the

type described comprising a housing having a relatively large cylinder bore and a communicating relatively small cylinder bore, a unitary differential piston having two diameters and arranged for reciprocation in corresponding cylinders, a second piston disposed in a cylinder communicating with said small cylinder and adapted to be activated by fluid under pressure said second piston being constantly spaced from said differential piston by a fluid column, said housing having a valve cylinder therein and having ports communicating with ports in said large and small cylinders and with pressure fluid supply means, a spring biased spool valve member longitudinally shiftable in said valve cylinder for controlling the actuation of said differential and said second piston and operable to first direct pressure fluid to act on said second piston for a portion of its travel and then automatically operable, upon said second piston encountering a predetermined restraining force, to direct pressure fluid to the large cylinder for actuating the piston therein thereby to transmit through the medium of the fluid confined between said second piston and the small diameter of said differential piston a force of increased intensity during the next portion of travel of said second piston, and valve means within said housing and operable by the travel of said differential piston to direct pressure fluid to act on said second piston for the final portion of its travel.
